CLAIM

The ornamental design for an eye closure portion for a brassiere, as shown and described.

DESCRIPTION

FIG. 1 is a perspective view of an eye closure portion for a brassiere according to our new and ornamental design; FIG. 2 is a front elevation view thereof; FIG. 3 is a rear elevation view thereof; FIG. 4 is a bottom plan view thereof; FIG. 5 is a top plan view thereof; FIG. 6 is a right side elevation view thereof; and, FIG. 7 is a left side elevation view thereof.

The dash-dot-dash lines define the bounds of the claimed design and form no part thereof. The dashed broken lines and the unshaded areas between the dashed broken lines and dash-dot-dash broken lines depict portions of the eye closure portion for a brassiere that form no part of the claimed design.
